UNITED STATES PATENT OFFICE.

AUGUSTUS REININGER, OF SAN FRANCISCO, CALIFORNIA.

DESIGN FOR A SCARF-PIN.

42,177.

Specification for Design.

Patented Feb. 13, 1912.

Application filed November 7, 1911. Serial No. 659,060. Term of patent 3½ years.

To all whom it may concern:

Be it known that I, AUGUSTUS REININGER, a citizen of the United States, residing at San Francisco, in the county of San Francisco and State of California, have invented a new, original and ornamental Design for Scarf-Pins, of which the following is a specification, reference being had to the accompanying drawing, forming part thereof.

Figure 1 is a front view of a scarf pin showing my new design; Fig. 2 is a side view thereof.

I claim:

The ornamental design for a scarf pin, as shown.

AUGUSTUS REININGER.

Witnesses:
